UNITED STATES PATENT OFFICE.

NICHOLAS BRAY, OF DUBUQUE, IOWA.

DESIGN FOR AN EYE-SHADE.

SPECIFICATION forming part of Design No. 24,921, dated November 26, 1895.

Application filed September 28, 1895. Serial No. 564,046. Term of patent 7 years.

To all whom it may concern:

Be it known that I, NICHOLAS BRAY, a citizen of the United States, residing in the city and county of Dubuque and State of Iowa, have invented and produced a new and original Design for Eye-Shades, of which the following is a full, clear, and close description.

My invention relates to designs for shades for the eyes; and it consists in the novel shape or configuration, which will be more fully described hereinafter.

The object of my invention is to produce a shade for the eyes having a pleasing ornamental outline or form.

Figure 1 is a perspective of a shade which embodies my invention. Fig. 2 is plan view of the blank from which the shade is formed.

The central portion A of the shade has two rounded edges *a* and *b*, which extend about parallel with each other, and at each end of the central portion A are formed the two side wings B. The lower edges of these wings are rounded or circular, and their inner edges are formed by a continuation of the inner line

or edge of the central portion A. The outlines of the two wings B are substantially pear-shaped, and the lower line of the shade forms a large scallop of three curves, while the inner line forms substantially a semicircle. The upper ends D of the shade are tapered to any desired degree and are substantially straight at their edges. The portions A and B may also be decorated.

A shade constructed as here shown and described is both novel and ornamental and produces a very pleasant effect upon the eye.

Having thus described my invention, what I claim, and desire to secure by Letters Patent, is—

The design for a shade for the eyes, substantially as shown and described.

In testimony whereof I affix my signature in the presence of two witnesses.

NICHOLAS BRAY.
